CLAIM

The ornamental design for an umbrella support for attachment to the handle of a golf cart, as shown and described.

DESCRIPTION

FIG. 1 is a top, front, and left side perspective view of an umbrella support for attachment to the handle of a golf cart showing my new design;

FIG. 2 is a front elevational view thereof;

FIG. 3 is a left side elevational view thereof, the right side being a mirror image of that shown;

FIG. 4 is a rear elevational view thereof;

FIG. 5 is a bottom plan view thereof; and,

FIG. 6 is a top plan view thereof.

FIG. 1
